UNITED STATES PATENT OFFICE.

ELLA E. PHELPS, OF UNION CITY, PENNSYLVANIA.

COMBINED CABINET AND TABLE.

1,133,743.

Specification of Letters Patent.

Patented Mar. 30, 1915.

Application filed January 13, 1913. Serial No. 741,735.

To all whom it may concern:

Be it known that I, ELLA E. PHELPS, a citizen of the United States, and a resident of Union City, in the county of Erie and 5 State of Pennsylvania, have invented a new and Improved Combined Cabinet and Table, of which the following is a specification.

This invention relates to a combined cabinet and table adapted to use either as a 10 table proper or as a cabinet with the top partially removed to uncover the cabinet, normally arranged to lie beneath the top, and within which there is formed a receptacle for work and materials, and within 15 which there are also provided drawers and compartments suitably arranged for holding the different articles which it may be desirable to use. Details of the internal arrangement of the cabinet may, of course, be 20 modified in many respects to suit the convenience of the user.

The purpose of my present invention is to provide such a combined table and cabinet 25 that it will have the appearance of a table when closed and when opened will afford a cabinet for accessible and orderly storage of the articles and the work upon which the user is engaged, and one in which 30 the cabinet shall be capable of use not only as a cabinet but in which a removable lower section of the cabinet may be used as a foot stool and in which, when the parts are all 35 in assembled relation, the foot stool forms the legs and support for the combined cabinet and table proper.

In carrying out my invention I provide a cabinet of the general character, as above indicated, formed in two sections, the lower 40 section of which is removably secured to the upper section and forming, when in position, a support for the upper section and when removed it is adapted to use as a foot stool. The cover which I provide for the 45 cabinet is adapted to use as a table top and is slidable upon the body of the cabinet so as to nearly or quite uncover the cabinet and the top is provided with a foldable leg and bracing members therefor, the leg and 50 the bracing members adapted in folded position to lie under the cover and over the top of the cabinet upon which the cover member slides. I also provide an extension member adapted to be removably secured to

the cover or table top proper in such a way 55 as to extend or increase the length of the cover or top when desired. In the construction of the cabinet and table I have found it desirable to provide new connecting and attaching means especially adapted to permit the desired coöperation of the several 60 parts of the cabinet and table.

The accompanying drawings illustrating an embodiment of my invention in a combined cabinet and extension table are as 65 follows:

Figure 1 is a side view of the cabinet and table with the extension top attached thereto and with the main top moved to its extreme extended position resting at one end 70 upon the body of the cabinet. Fig. 2 is a view of the parts shown in Fig. 1 as seen from the left. Fig. 3 is a side elevation of the cabinet and table with the extension member removed and with the cover or top 75 in its normal central position adapting the device to use as a table. Fig. 4 is a plan view of the cabinet with the cover removed. Fig. 5 is a transverse sectional view of the parts seen in Fig. 4 taken along the line 80 $x-y$ of Fig. 4. Fig. 6 is an enlarged view of part of the cabinet near the top thereof and shows the same in section taken along the line $x-y'$ of Fig. 4. Fig. 7 is a view of the cabinet proper as seen from the under side. Fig. 8 is a top or plan view and Fig. 9 is a side view of the lower section of 85 the cabinet when removed for use as a foot stool. Fig. 10 shows, in perspective, one of the removable panel sections adapted to be 90 ornamented to improve the appearance of the cabinet.

Similar parts are designated by similar reference characters throughout the several figures of the drawings.

Referring to the drawings, in carrying out my invention I provide a main body portion or upper section D of the cabinet all four sides d of which are formed alike and have corner pieces d' arranged on each 100 of the four edges of each of the sides d . These members d' are recessed or rabbeted on their rear sides to provide grooves for receiving the panel pieces P which are made removable for the purpose of cleaning or 105 changing the ornamentation thereon. The construction in this respect is indicated more clearly in Figs. 5 and 6, while such a panel

is shown in perspective in Fig. 10. Within the panels P and the cover pieces d^1 there is provided a preferably tapered box-like member, the sides of which d are continuous.

5 Around the top of the cabinet section D there is provided a cap member d^2 between which and an inwardly extending cap member d^3 there is provided a space for the insertion and removal of the panels P. Around the upper edge of the sides d and on the inside of the cabinet section D there is provided a reinforcing member F engaging under the inwardly extending cap member d^3 . On two sides of the section D and around the inside thereof there are provided suitable receptacles V, V^1 , V^2 and V^3 , and within the receptacle V^2 there may be provided a cushion for pins. These receptacles are formed between the sides d near the top thereof and the partition members v , v^1 and v^2 . The receptacle V^1 is deeper than the receptacles V, V^2 and V^3 , as indicated more clearly in Fig. 6. The bottoms v^3 of the receptacles, V, V^2 and V^3 are on the same level with a ledge member E carrying suitably upwardly extending pins o for receiving spools of thread. Beneath the receptacle V^2 there is seen a drawer member N provided with a suitable handle n, while under the receptacle V there is similarly located a drawer N^1 also provided with a handle or knob n, and beneath these drawers N and N^1 there is provided a supporting member 35 E¹ resting upon a reinforcing cleat m^1 . Reinforcing corner pieces m are provided inside of the case extending from the bottom B thereof upwardly to the reinforcing members m^1 and a spacing block m^2 is provided 40 at the left hand end of the drawer N, as seen in Fig. 5. The main body of the cabinet section D comprises a receptacle Z which may be used for receiving and storing the work.

45 The cabinet section D is recessed on the under side, as seen in Fig. 5, being provided with reinforcing cleats b^1 engaging under the bottom B, the space within which is adapted to receive the upper portion of the 50 lower or foot stool section G of the cabinet, the upper portion of which latter is upholstered as indicated at G¹ in Figs. 8 and 9. This lower or foot stool section G is provided with legs g shouldered at their upper 55 ends to provide upwardly extending tenons g^1 into which are suitably framed the side members g^2 and the bottom g^3 for inclosing and supporting the upholstered portion G¹ and also for securing the legs together in 60 proper position.

Extending downwardly from the bottom g^3 there are seen four screws u preferably round headed and each adapted to be engaged by the outer and slotted end of a corresponding link U pivotally secured by a

similar screw to the under side of the reinforcing cleats b^1 of the upper cabinet section D in such a way, as indicated in Fig. 7, that these links may be used to lock the lower or foot stool section G to the upper 70 section D. On the outside of the cabinet section D and on each side thereof centrally disposed between the legs g of the lower section there are provided ornamental foot members b adapted to form suitable supporting feet for the upper section of the cabinet when removed from the lower section or foot stool.

On the cabinet section D there is slidably supported the table top T which is provided with downwardly extending side frame pieces t having suitable inwardly extending flanges, not shown, along their lower edges engaging under the outwardly extending cap pieces d^2 of the cabinet, and, also, across its 85 ends with downwardly extending frame pieces H¹ of the same width as the pieces t and co-operating therewith to form a continuous frame work around the under side of the top T. One or both of the end frame pieces 90 H¹ are hinged in place and adapted to swing upward against the under side of the table top to permit the same being slid on and off of the cabinet section. At one end of the top T there is also secured by means of a 95 hinge a leg A which supports one end of the table top from the floor when such top is in extended position, as shown in Fig. 1, and which is swung upward so as to lie against the under side of the top T and unseen 100 when the cover member and cabinet occupy the relative positions indicated in Fig. 3. As the particular construction of the table top is not claimed as a part of this invention, the manner of hinging the above mentioned swinging members thereto has not been shown.

When, for any reason, there is needed a longer table top than the main top T, the extension T¹ may be made use of. This 110 member is provided with downwardly extending frame pieces t¹ similar to the ones t except that the pieces t¹ extend to the right of the top T¹, under the top T and against the frame pieces t. At the left hand end 115 of the extension top T¹ there is rigidly secured the downwardly extending frame piece H² and within which and hinged to the under side of the top there are a pair of supporting legs A¹ connected by a cross 120 bar a². The right hand end of the extension top, with respect to Fig. 1, is removably secured by any suitable locking means to the left hand end of the main top T, and when such extension is not in use the legs A¹ are 125 swung so as to lie against the under side thereof. Bracing members a on the top T, and a¹ on the extension T¹, are hinged to the under side of their respective top members and are adapted to be swung downward 130

into operative position for bracing the supporting legs A and A¹, being held in such position by links r thereon engaging suitable screws r¹ therefor in the legs A and A¹.

- 5 For locking the top T in the position indicated in Fig. 1, screw hooks I may be made use of secured to the frame pieces on the under side of the top and normally held in inoperative position by engaging with 10 their free ends over pins i¹, and adapted in their operative positions to engage with their free or hooked ends into eyes therefor i screwed into the edge of the left end, with reference to Fig. 1, of the cap member d².
- 15 When the device is used as a table proper the top T is only made use of and the parts are moved to the relative positions indicated in Fig. 3. When, however, the device is used as a combined cabinet and table the top 20 T may be moved to the position, substantially as indicated in Fig. 1, either with or without the extension top T¹, which latter, when used, is secured in the position, also, such as indicated in Fig. 1, and in the manner 25 already described. When the device is used as a combined extension table and cabinet the sections D and G of the cabinet are kept together. When, however, the use of the top T or the extension thereof may both 30 be dispensed with the lower section G may be used as a foot stool, while the upper section D is supported by means of the foot pieces b, on the floor near the user.

It is believed from the foregoing description of the operation and method of attachment of the several parts of my combined table and cabinet that the several uses to which the same may be advantageously put

are sufficiently clear to call for no further explanation herein.

What I claim is:

1. In a device of the character described, a cabinet section having a recess formed in the under side thereof, legs for supporting said section, such legs being carried by a base section, an upholstered top on said base section adapted to engage within said recess, and means provided on the two sections for removably connecting them. 45
2. In a device of the character described, a cabinet section having a recess formed in the under side thereof, legs for supporting said section, such legs being carried by a base section, a reduced top on said base section adapted to engage within said recess, means provided on the two sections for removably connecting them, and foot members 50 on the sides of said cabinet section for supporting the same when removed from said base section. 55
3. In a combined cabinet and table, a cabinet section having a table top slidable thereon and removable therefrom and a recess formed in the under side thereof, legs for supporting said section, such legs being carried by a base section, a reduced top on said base section adapted to engage within said recess, means provided on the two sections for removably connecting them, and foot members 60 on the sides of said cabinet section for supporting the same when removed from said base section. 65
6. In a combined cabinet and table, a cabinet section having a table top slidable thereon and removable therefrom and a recess formed in the under side thereof, legs for supporting said section, such legs being carried by a base section, a reduced top on said base section adapted to engage within said recess, means provided on the two sections for removably connecting them, and foot members 70 on the sides of said cabinet section for supporting the same when removed from said base section. 75
